DRAWER GUIDE OR SIMILAR ARTICLE

Robert L. Jones, 308 Oxfordshire Lane,
Louisville, Ky. 40207

Filed July 13, 1970, Ser. No. 23,933

Term of patent 14 years

Int. Cl. D6—99

U.S. Cl. D6—191

FIG. 1

FIG. 1 is a front perspective view of a drawer guide showing my new design with parts thereof shown broken away to illustrate indeterminate length;

FIG. 2 is a fragmentary top plan view thereof; and

FIG. 3 is a fragmentary side elevational view thereof.

I claim:

The ornamental design for a drawer guide or similar article, substantially as shown and described.
